UNITED STATES PATENT OFFICE

157,406

AIR CIRCULATOR

Joseph Palma, Jr., Chicago, Ill., assignor to Cory Corporation, Chicago, Ill., a corporation of Delaware

Application November 23, 1948, Serial No. 149,785

Term of patent 14 years

(Cl. D26—7)

To all whom it may concern:

Be it known that I, Joseph Palma, Jr., a citizen of the United States, residing at Chicago, in the county of Cook and State of Illinois, have invented a new, original, and ornamental Design for an Air Circulator, of which the following is a specification, reference being had to the accompanying drawing, forming a part thereof, wherein:

Figure 1 is a perspective view, looking from the front and one end of the air circulator, showing my new design;

Fig. 2 is an end elevation thereof; and

Fig. 3 is a perspective view looking from the rear and one end of the air-circulator.

I claim:

The ornamental design for an air circulator, as shown.

JOSEPH PALMA, JR.
